UNITED STATES PATENT OFFICE.

PETER C. HENDERSON, OF EAST CLEVELAND, OHIO.

BUNG BUSHING AND CLOSURE FOR SHEET-METAL CONTAINERS.

Application filed November 12, 1924. Serial No. 749,445.

This invention relates to an improved bung bushing, in some cases known as a bung bushing, for use with sheet metal containers such as drums, barrels, tanks and the like, and to a closure therefor; and its objects are to provide an inexpensive yet highly efficient device of this character that is simple of construction and is convenient of attachment to sheet metal walls, is so designed as to compensate for such slight irregularities as are liable to be attendant upon quantity production, and whose manufacture and installation are adapted to prevailing practice.

In furtherance of certain of the foregoing objects, the device is made of sheet metal, as illustrated in the accompanying drawing wherein Fig. 1 is a sectional view through my improved bushing and closure applied to a sheet metal wall; Fig. 2 is an outside view, and Fig. 3 an inside view, of what is shown in Fig. 1; Fig. 4 is a central section through the bushing showing its condition before being applied to a wall; Fig. 5 is a similar view of the bushing, illustrating the first step in applying the same to a wall; Fig. 6 is a central section through the bushing showing its condition when applied to a wall, the wall in this view being indicated in dot and dash lines; Fig. 7 is a sectional detail on the line 7—7 of Fig. 6; and Fig. 8 is a view, similar to Fig. 6 but omitting the wall, of a modified form of the invention.

As above stated, my improved bushing is intended for use with sheet metal containers and the wall of such a container is designated 1 in the drawing. Preparatory to applying the bushing to the wall 1, the wall is punched to provide an opening and the material about said opening is drawn to form a cylindrical flange 2 that is flared slightly at its inner end.

The bushing, which is drawn from sheet metal of a suitable thickness, comprises a neck 3 and a base 4 that extends outwardly from one end of the neck, and a plurality of lugs 5 which project from the edge of the base. To facilitate the bending of the lugs and the application of the bushing to the flange 2 of the wall 1, in the manner presently to be described, the lines along which the lugs are bent are straight, and this imparts to the base 4 a hexagonal shape, as shown in Fig. 3, due to the fact that

there are six lugs embodied in the present design. The shape would be changed, of course, by increasing or reducing the number of lugs. Formed within the surface of the base 4 are radial grooves 6 which are shown as opposite the longitudinal centers of the lugs 5, and adapted for cooperation with these grooves are ribs 7 that are formed on the inner sides of the lugs.

After the bushing is applied to the flange 2, as illustrated in Fig. 5, the parts are compressed, as by means of a suitable machine, which causes the lugs 5 to be forced inwardly and downwardly and the inner end of the flange 2 outwardly so that the said inner end of the flange is clamped between the lugs and the base, while portions of the flange are displaced by the ribs 7 into the grooves 6, this condition being illustrated in Figs. 1, 6 and 7. The bushing is thus effectively locked against turning with respect to the wall.

The neck 3 is internally threaded for the reception of the threaded inner end of a closure or plug 8 which is preferably formed of sheet metal and is provided, at its outer end, with a flange 9 on the inner surface of which is formed an annular rib 10. The flange 9 is so shaped as to adapt it to the reception of a wrench, the same being shown as hexagonal in the present instance. A gasket 11 of suitable packing material is inserted between the flange 9 and the adjacent surface of the wall 1, and when the closure or plug 8 is screwed into the neck 3 the annular rib 10 embeds itself into the gasket thereby to effect a leak-proof joint between the flange and gasket, the gasket in turn, being pressed with a leak-tight fit against the wall 1. By providing the rib 10, the plug or closure may be tilted slightly with respect to the surface of the wall and yet the joint will be leak-proof by reason of the fact that the rib is embedded within the gasket entirely throughout its circumference, a little less on one side than on the other, however, and the gasket is pressed with substantially the same degree of pressure all the way around against the wall 1. This feature insures a tight joint notwithstanding slight irregularities which are liable to occur in the manufacture of the bushings and in their application to the walls of containers.

In the modification illustrated in Fig. 8, 110

an annular groove 6^a is substituted for the radial grooves 6 of the previously described form, and arcuate beads 7^a, on the lugs 5, cooperate with said groove.

5 Having thus described my invention, what I claim is:

1. In combination, a sheet metal wall having an opening and a flange surrounding said opening, and a bushing comprising a neck and a base at one end of the neck and a plurality of lugs extending inwardly and over the base from the outer edge thereof, the inner end of the aforesaid flange being flared outwardly and clamped between the base and said lugs, the base and lugs having, on the one hand radial grooves, and on the other, ribs which mate with said grooves, the ribs serving to project parts of said flange into the grooves when the parts are pressed together.
2. In combination, a sheet metal wall having an opening and a flange surrounding said opening, and a bushing comprising a neck and a base at one end of the neck and a plurality of lugs extending inwardly and over the base from the outer edge thereof, the inner end of the aforesaid flange being flared outwardly and clamped between the base and said lugs, the base having radial grooves and the lugs having ribs that mate with said grooves and serve to project parts

of the flange into the grooves when the parts are pressed together.

3. In combination, a sheet metal wall having an opening and a flange surrounding said opening, and a bushing comprising a neck and a base at one end of the neck and a plurality of relatively wide lugs bent along substantially straight lines inwardly and over the base from the outer edge thereof, the adjacent ends of adjoining lugs meeting on substantially radial lines, the inner end of the aforesaid flange being flared outwardly and clamped between the base and said lugs.

4. In combination, a sheet metal wall having an opening and a cylindrical flange surrounding said opening, and a bushing comprising a neck and a base at one end of the neck and a plurality of lugs extending inwardly and over the base from the outer edge thereof, the lateral edges of adjacent lugs meeting on substantially radial lines, the inner ends of said lugs being curved and collectively forming a circular opening through which the aforesaid flange extends, the inner end of said flange being flared outwardly and clamped between the base and said lugs.

In testimony whereof, I hereunto affix my signature.

PETER C. HENDERSON.
